FILLING FEELER

Horace H. Burdett, Hopedale, Mass., assignor to
Draper Corporation, Hopedale, Mass., a corpora-
tion of Maine

Application February 24, 1937, Serial No. 127,375

2 Claims. (Cl. 139—287)

The present invention pertains to filling feelers for looms and has more particular reference to filling feelers of the mechanical type including a feeler blade having a filling-engaging tip which is directly engaged by the filling supply in the shuttle.

As commonly constructed, the filling feeler blade of such feelers is movably mounted on a feeler stand and is adapted, when moved in a predetermined manner, to control the filling replenishing mechanism of the loom. The movement of the feeler blade is effected by engagement of the filling supply, or a bare filling carrier, with the tip of the feeler blade.

15 An object of the present invention is to provide a filling feeler including a movable feeler blade as aforesaid, which feeler blade shall have a novel and improved feeler tip as will more fully appear.

20 The preferred embodiment of the invention is illustrated on the accompanying drawing, of which:

Fig. 1 is a perspective view of my improved filling feeler in position on a loom;

25 Fig. 2 is a plan view of said filling feeler with the cover removed, this view also showing in dotted lines a second position which the feeler blade assumes in operation of the loom; and

30 Fig. 3 is a view similar to Fig. 2 but illustrating the action of the feeler when the filling supply becomes substantially depleted.

The drawing shows the left hand end of a lay 1, which reciprocates toward and from the front of the loom and which is provided with a shuttle box 2 for receiving a shuttle 3. The shuttle contains a filling carrier, such as bobbin 4, which carries the supply of filling F. The shuttle is picked back and forth along the lay to form picks of the filling thread in the shed (not shown), as is well known in the art. When the filling supply on the bobbin 4 is substantially exhausted the bobbin is automatically ejected from the shuttle and replaced by a fresh bobbin, by mechanism not shown which is controlled by the filling feeler mechanism to be described.

45 Such filling feeler mechanism operates to determine the condition of the filling supply by feeling of the same through a slot 5 in the front wall of the shuttle and when a predetermined state of exhaustion of the filling supply is detected a rod 6 is moved to initiate operation of the bobbin changing mechanism as above stated.

The feeler mechanism shown includes a feeler stand 7 and cover plate 8 secured thereto, the stand being fixed to a bracket 9 at the front of

the loom in front of the shuttle box 2. The filling feeler blade includes a rearwardly extending portion 10, a laterally extending arm 11 at the front of the portion 10, and a feeler tip 12 at the rearward end thereof. This blade is 5 mounted directly on the feeler stand for movements forwardly and rearwardly of the loom and for side slipping movements against the action of a spring 13, as is more fully disclosed in patent to Brown and Repass, No. 1,593,426, granted 10 July 20, 1926.

The operation of the feeler is well known in the art but may be briefly stated. When the lay moves forwardly with the shuttle 3 in the shuttle box 2, the feeler tip 12 enters the slot 5 in the 15 shuttle. If, at such time, there is ample filling on the bobbin the filling supply F strikes the feeler tip 12 and moves the feeler blade forwardly from the full line position of Fig. 2 to the dotted line position thereof, without moving the rod 6. 20 When the filling supply F becomes substantially exhausted, the feeler tip is struck by the bobbin 4 and will slide therealong, thereby moving rod 6, as suggested by Fig. 3.

25 The feeler tip 12 is of novel construction devised particularly to prevent damage to the filling thread from the repeated striking of the filling supply F against the feeler tip, and to prevent premature sliding or side-slipping of the feeler blade. To this end, the feeler tip 12 comprises a strip of leather bent into a loop the bight 14 of which extends rearwardly from the feeler blade and the rounded exterior surface 16 of which is adapted to engage the filling supply F in the shuttle. The legs 17, 17 of the 30 loop are fixed to the rearward end of the feeler blade.

35 A strip of leather, when formed into a loop, is more or less resilient or yieldable, according to the nature of the material and the thickness 40 of the strip. Such a loop is, therefore, less apt to injure the filling thread. In the particular embodiments shown on the drawing, the feeler tip 12 is formed of a strip of flexible leather. The strip of material of which the feeler tip is formed 45 may be of sufficient thickness that the loop is self-sustaining, i. e., the loop will keep its shape and will not be materially deformed by the blows to which it is subjected in operation. The thickness of the strip must be determined in accordance with several factors such as the nature of the leather and its degree of flexibility, the strength of the spring 13, and possibly the speed of operation of the loom. I find that if the feeler tip is made of leather it will have the desired 50 55

characteristics if it is constructed substantially in the proportions shown on the drawing.

The legs 17 of the feeler tip extend forwardly from the bight 14 of the loop and, in the form 5 shown, are substantially in parallelism. These legs are positioned on opposite sides of the rearward end of the portion 10 of the feeler blade. Fastening means such as rivets 18 pass through the legs 17 and the portion 10 of the feeler 10 blade to secure the feeler tip to the feeler blade. Such rivets may be removed should it be desired to provide a new feeler tip for the feeler blade.

I find that the filling thread often operates more satisfactorily if the rounded filling engaging 15 surface 16 is provided with filling engaging teeth as shown. I also find that the leather tip may be prevented from abrading or catching the filaments of some artificial silk filling threads if the tip is coated with a solution of cellulose dissolved in acetone.

Having fully disclosed the preferred embodiment of my invention, I claim:

1. A filling feeler including a side-slipping feeler blade having a substantially straight rearwardly extending stem and a feeler tip at the rearward end of said stem, said tip comprising a strip of leather bent into a loop the bight of 5 which extends rearwardly from said stem and is provided with filling-engaging teeth, the legs of said loop extending forwardly and being fixed to said stem.

2. A filling feeler including a side-slipping 10 feeler blade having a substantially straight rearwardly extending stem and a feeler tip at the rearward end of said stem, said tip comprising a loop formed from a strip of leather of sufficient thickness that said loop is substantially self-sustaining, the bight of said loop extending rearwardly from said stem and the rounded exterior 15 surface thereof being provided with filling-engaging teeth, the legs of said loop extending forwardly in substantial parallelism and being fixed 20 to opposite sides of said stem.

HORACE H. BURDETT.
